OR D 11,886

No. 11,886

JULY 27, 1880

UNITED STATES PATENT OFFICE.

OTIS G. CLARK, OF TROY, AND DANIEL D. BUCKLIN, OF LANSINGBURG,
EXECUTORS OF NICHOLAS S. VEDDER, DECEASED, AND TOBIAS S. HEISTER,
OF LANSINGBURG, NEW YORK; SAID HEISTER ASSIGNOR TO SAID
CLARK AND BUCKLIN AS EXECUTORS.

DESIGN FOR A MAGAZINE-STOVE.

SPECIFICATION forming part of Design No. 11,886, dated July 27, 1880.

Application filed June 14, 1880. Term of patent 3½ years.

To all whom it may concern:

Be it known that NICHOLAS S. VEDDER, deceased, late of the city of Troy, in the county of Rensselaer and State of New York, and TOBIAS S. HEISTER, residing in the village of Lansingburg, in said county and State, did, in the life-time of said NICHOLAS S. VEDDER, jointly invent and produce a certain new and original Design for Magazine-Stoves; and

10 that OTIS G. CLARK, residing in the city of Troy, aforesaid, and DANIEL D. BUCKLIN, residing in the aforesaid village of Lansingburgh, are the executors of the last will and testament of said NICHOLAS S. VEDDER, deceased; and we, the said OTIS G. CLARK, DANIEL D. BUCKLIN, and TOBIAS S. HEISTER, do hereby declare that the following is a specification of the said new design, reference being had to the accompanying cut, print, or engraving.

20c One feature of this invention is the design for the base-section A, composed of the quadrilateral bottom plate, B, having truncate corners with flat inclined outer faces, c c', and the scalloped ornamentation d along its inner border, and the two quadrilateral sub-sections having truncate corners, flat inclined faces e f g h, and ornamental moldings i and i' along the lower parts thereof, all shaped and arranged together as represented in the afore-
30 said print.

Another part is the design for the fire-pot section J, composed of the bowl-shaped open-work upper portion, k, having the series of upwardly-flaring ribs l, with the angular ornaments l' on the middle part thereof, and the lower portion having the horizontally-oblong doors m, each with the two illumination-apertures, n, surrounded by the series of oblong ornamentations o, and separated by the differently ornamented bars o', all shaped, arranged and combined as shown in the aforesaid engraving, in combination with the design for the doors P of the combustion-chamber, each being composed of the five illumination-

45 apertures q q' q² q³ q⁴, of which two are of oblong quadrilateral form with truncate corners, and constitute the lower row, and the other three are of upwardly-tapering quadrilateral form with truncate corners, and arranged in an upper row, and the whole surrounded by the border r, having the series of interrupted oblong ornaments thereon, and separated by the differently ornamented bars s, all shaped, arranged, and combined, as represented in the aforesaid cut.

50 Another feature is the design for the upper section, T, the same being composed of panels, each consisting of the central compound ornament, u, inclosed by the ornamental frame v on the surface w, surrounded by compound border x, having the series of scalloped and diamond - like ornamentations thereon, all shaped and arranged together substantially as represented in the aforesaid print.

55 Another feature is the design for the leg Z, composed of the upper horizontally-oblong panel, a, having the scallop-border b, and central ornament, b', the upwardly - swelling middle section, j, having the central cruciform ornament, p, on the ground p', and the ornament 60 t' on the concavely-contracted lower section, t, all shaped, arranged, and combined as shown in the accompanying engraving.

65 What is claimed as the joint invention of the aforesaid NICHOLAS S. VEDDER and TOBIAS S. HEISTER is—

70 1. The design for the base-section A, composed of the parts B, c, c', d, e, f, g, h, and i i', all shaped and arranged together, as set forth.

75 2. The design for the fire-pot section J, composed of the parts k, l, l', m, n, o, and o', all shaped and arranged together as shown and described, in combination with the design for the doors P of the combustion-chamber, consisting of the parts q, q', q², q³, q⁴, r, and s, all shaped, arranged, and combined as shown and described.

(over)

3. The design for the upper section, T, composed of panels, each consisting of the parts *u*, *v*, *w*, and *x*, all shaped and arranged together, as set forth.
4. The design for the legs Z, consisting of the parts *a*, *b*, *b'*, *j*, *p*, *p'*, and *t* *t'*, all shaped, arranged, and combined as shown and described.

In testimony whereof we hereunto set our

hands, in the presence of two subscribing witnesses, this 10th day of June, 1880.

OTIS G. CLARK,
DANIEL D. BUCKLIN,
Executors of Nicholas S. Vedder, deceased.

TOBIAS S. HEISTER.

Witnesses:

JAMES A. GILMAN,
CHESTER BASCOM.
